UNITED STATES PATENT OFFICE

EDWARD HOUSER, OF MUNCIE, INDIANA, ASSIGNOR TO THE MOORE COMPANY, OF MUNCIE, INDIANA, A CORPORATION OF INDIANA

FORMING MACHINE

Application filed December 23, 1929. Serial No. 416,172.

My invention relates to forming machines and is of particular service in shaping the borders that surround coiled spring mattresses, these borders being made of rods 5 which the coiled springs are connected.

In one feature of my invention an anvil is employed which has an arcuate working surface upon which the rod or other object to be shaped is pressed by means of a forming 10 member, preferably a roller, which is mounted to turn upon the axis of the anvil.

In another feature of the invention two forming devices may be employed, each preferably made as hitherto generally described.

15 These two forming devices simultaneously operate upon a rod to bend the end portions thereof at right angles to the intermediate portion to form the rod into U shape. Two of these bent rods with their ends welded together may constitute the mattress border 20 hitherto mentioned.

The invention in its preferred embodiment, is inclusive of reciprocating rack bars which are in mesh with arcuate racks or gears that 25 are concentric with the anvils, these two rack bars being engaged by opposite sides of gearing to cause them to be simultaneously moved inward and simultaneously moved outward to operate simultaneously upon the rod or 30 other object which is to be shaped at separated parts. A fly wheel is brought into actuating relation with another rack bar that operates the gearing that pertains to the first mentioned rack bars. The mechanism 35 through which the fly wheel operates is preferably similar to that employed in punch presses, and controlled by similar pedestal operated clutching mechanism. The rack bar that is directly controlled by the fly wheel 40 is desirably vertically arranged and is moved up and down for each cycle of operations, causing outward and inward movement of the rollers for each cycle of operations.

The invention has other characteristics and 45 will be more fully set forth in connection with the accompanying drawings in which Fig. 1 is an elevation illustrating the preferred embodiment thereof; Fig. 2 illustrates two halves of a border, which may be formed by the machine, these two halves being welded

together, some of the springs of the mattress having such a frame being also illustrated; Fig. 3 is a sectional view on line 3—3 of Fig. 1; Fig. 4 is a sectional view on line 4—4 of Fig. 3; Fig. 5 is a sectional view on line 5—5 of Fig. 1; Fig. 6 is a sectional view on line 6—6 of Fig. 1, on a larger scale; Fig. 7 is a sectional view on line 7—7 of Fig. 1; and Fig. 8 is a sectional view on line 8—8 of Fig. 1, also on a larger scale.

The mechanism of my invention has, as its main mounting, the press table 1 having a pedestal 2. The mounting for such mechanism is also inclusive of the mounting bar 3 which is secured to the table by means of the assembling plate 4 which is bolted to both bar and table. Anvils 5, and 5' are bolted to the end portions of the mounting bar 3. The bolts 7 that fasten the anvils to the bar are desirably passed through slots 8 in the anvils and extending along the bar, whereby the anvils may be adjusted somewhat along the bar and with respect to each other. The bar is further supported by two pedestals 9 and 10 which are respectively bolted to the anvils 5 and 5'.

The rods or blanks 11 which are to be shaped are carried by the brackets 12 and 13 which are bolted to the pedestals 9 and 10, respectively. The bracket 12 has two pocketed portions 12', 12" and the bracket 13 has two pocketed portions 13' and 13". The unformed rods are carried in the pockets 12', 13'. After the rods have been shaped, they are carried in the pockets 12", 13".

Each rod 11 that is to be shaped is placed upon the anvils 5 and 5', the position of such rod being defined by the stop 14 which is provided upon the left hand end of the mounting bar 3. The left hand end of the rod 11 that is to be operated upon extends sufficiently to the left of the anvil 5 and the right hand end of this rod extends sufficiently to the right of the anvil 5', so that after the forming mechanism has been applied to the rod, the end portions of such rod will be downwardly deflected sufficiently to make a U-shaped half 15 of the frame, Fig. 2. I will describe the forming mechanism at the left hand end of the machine, the forming mecha-

nism at the right hand end of the machine being similar thereto, similar characters of reference being applied to the latter forming mechanism with prime exponents added.

5 The member which cooperates with the anvil 5 to turn the left hand end of the rod 11 is inclusive of a lever 16 which carries a roller 17. The lever 16 is journaled upon a stationary shaft 18, which is bolted to the adjacent anvil 5. This anvil has an arcuate forming surface which is coaxial with the lever and which bulges toward the adjacent end of the machine. When the lever 16 is turned toward the adjacent end of the machine, said roller rolls upon the rod 11 that is interposed between it and the anvil, whereby the adjacent end of said rod is turned at right angles to the intermediate portion of this rod. Both ends of the rod 11 are operated upon simultaneously, as will later appear, whereby the rod is transformed into one of the U-shaped members 15, Fig. 2. The roller 17 is journaled upon a stud 19 having a reduced portion that passes through an upright slot 20 in the lever 16. A nut 21 is screwed upon said stud to clamp the lever between it and the larger portion of the stud, whereby the position of the forming roller 17 is determined. A block 22 is also slidingly received in the slot 20. A bolt 23 is screwed through the outer end of the lever into engagement with said block, whereby the block engages the stud and serves to prevent the stud and the roller thereon from being tilted 35 in the forming operation. The lever 16 is operated by a mutilated or arcuate gear 24 which is normally fixed with respect to and is coaxial with such lever. Said mutilated pinion or arcuate rack 24 is in mesh with the teeth of a reciprocable bar 25. This rack bar is directed at its outer end by the channel bar 26 which is upon the bracket 27. This bracket is bolted to the mounting bar 3, the mounting bolts 28 passing through arcuate 40 slots in the bracket 27 that are coaxial with the lever 16, whereby the position of the guide 26 is adjusted to compensate for change in position of the guide that would result from the adjustment effected by the corresponding bolts 7. The inner end of the rack bar 25 is guided by the table 1, which is formed with a guiding groove, one side of which is engaged by one side of said rack bar. A spur gear 29 engages the rack teeth upon the inner end of the bar 25 whereby said rack bar is moved longitudinally along the guides provided for it and to effect oscillating movement of the corresponding arcuate rack 24.

55 The spur gears 29 and 29' are coaxial and 60 in fixed relation. They are together turned by a spur pinion 30 which is coaxial therewith and fixed with respect thereto. The shaft 31 for the gears 29, 29' and 30 is journaled in bearings 32 which are carried by the table 1. 65 The pinion 30 is in mesh with an upright

reciprocable rack bar 33. This rack bar has a predetermined extent of movement in each of its directions of reciprocation, whereby the rack bars 25 and 25' are reciprocated in opposite directions, these reciprocations of these two rack bars being simultaneous. When the rack bars 25 and 25' are moved outwardly, they simultaneously operate upon the end portions of the rod 11 that is placed upon the anvils 5 and 5' to form this rod into a 75 U shape. In this movement of said two rack bars, the roller 17 is moved counterclockwise over the arcuate surface of the anvil 5 and the roller 17' is moved clockwise over the arcuate surface of the anvil 5'. To prevent the rod 11 that is being operated upon from buckling upwardly between the anvils, I provide abutments 34 upon the mounting rod 3 and which overlie such rod. These abutments also serve as positioners for the rod, as such rod is being located upon the anvils. 80

85 Any suitable means may be employed for reciprocating the upright rack 33. The means illustrated is inclusive of a fly wheel 35 from which motion is imparted to the rack bar during automatically limited periods. The usual mechanism employed for this purpose is found in punch presses, for example. It will not be necessary, therefore, to describe this mechanism in detail, it being sufficient to say that the rack bar 33 is mounted in a cross head 36 which is reciprocated within guides 37 operated by the pitman 38 which is operated by the crank 39 that, in turn, is operated by the fly wheel 35 through the intermediation of well known clutching mechanism 40, each time this clutching mechanism is brought into action by the depression of the foot lever 41 which is connected with the clutching mechanism by the link 42, as is well understood by those skilled in the art. 90 Each time the foot lever 41 is depressed, the rack bar 33 is first lowered and then elevated, whereby the rack bars 25 and 25' are first moved outwardly and then are inwardly withdrawn, with the results stated. After each complete cycle of operations of the rack bars and associated parts the formed rod is ejected. This ejecting means is inclusive of pawls 43, 43' which are respectively pivotally mounted upon mountings 44 and 44' that are carried by the rack bars 25 and 25', respectively. These pawls, in their outward movements with the rack bars that carry them, ride over ends of the bell crank levers 45 and 45', but when the said pawls move inwardly, they are brought into engagement with these bell crank arms after the rod has been formed and force movement of the bell cranks in horizontal planes, the other ends of said bell cranks pushing laterally upon the formed rod to move this rod from the anvils and deposit the intermediate portion thereof in the pockets 12², 13². After the bell cranks have performed their function, they are retracted 105 110 115 120 125 130

by the coiled springs 46, 46' against stop pins 47, 47' that define the idle positions of said bell cranks.

The guide 48' that pertains to the inner end 5 of the rack bar 25' is adjustably mounted upon the cross head guides 37 to compensate for adjustment effected at the corresponding bolts 7. The arcuate rack or gear 24' is secured in fixed relation with a corresponding lever 16' by means of bolts 49 which pass through slots in said gear that are coaxial therewith for purposes of adjustment. The two shafts 18, 18' have reduced portions which pass through the struts 50, 50' and are clamped thereto by nuts 51, 51'. These struts are bolted to the pedestal 2. They take part in holding said shafts 18, 18' at right angles to the mounting bar 3. The shafts 18, 18' pass through horizontal slots 15 that are formed in the struts 50, 51', whereby 20 adjustment of the rear ends of the shafts may be effected, the front ends of the shafts being adjustable, as previously described.

It will be observed that the gears which 25 operate the racks 25 and 25' are of different diameters and that the anvils in association with these racks are of corresponding diameters. This enables the formation of curvatures of differing diameters in the corners 30 of the formed rods, it being usual to make the borders or frames that surround the mattresses of such different curvatures at their corners, as illustrated in Fig. 2.

Changes may be made without departing 35 from the invention.

Having thus described my invention, I claim:

1. A forming machine including one member 40 in the form of an anvil having an arcuate work engaging surface; a work engaging member coaxial with said work engaging surface, said members being relatively rotatable and related to receive and engage work therebetween; a gear in connection with one 45 of the aforesaid members to turn it with respect to the other; an operating reciprocating rack in mesh with said gear; and an ejector operable by said rack and related thereto to be operable thereby after the conclusion of the forming operation.

2. A forming machine including one member 55 in the form of an anvil having an arcuate work engaging surface; a second member in the form of a roller opposite the anvil; a mounting on which the roller turns, said anvil and roller being related to receive and engage work therebetween, said mounting and anvil being coaxial and relatively rotatable; a gear coupled with one of the latter two elements; a reciprocating operating rack in mesh with said gear; and an ejector operable by said rack and related thereto to be operable thereby after the conclusion of the forming operation.

3. A forming machine including one mem-

ber in the form of an anvil having an arcuate work engaging surface; a work engaging member coaxial with said work engaging surface, said members being relatively rotatable and related to receive and engage work therebetween; a gear in connection with one of the aforesaid members to turn it with respect to the other; an operating reciprocating rack in mesh with said gear; an ejector operable by said rack and related thereto to be operable thereby after the conclusion of the forming operation; a bell crank lever positioned to engage and eject the formed work; and a pawl coupled with said rack and in escaping relation with the bell crank when the rack is moving in a functioning direction and having operating engagement with said lever when the rack is moving in its non-operating stroke.

4. A forming machine including one member 85 in the form of an anvil having an arcuate work engaging surface; a second member in the form of a roller opposite the anvil; a mounting on which the roller turns, said anvil and roller being related to receive and engage work therebetween, said mounting and anvil being coaxial and relatively rotatable; a gear coupled with one of the latter two elements; a reciprocating operating rack in mesh with said gear; an ejector operable by said rack and related thereto to be operable thereby after the conclusion of the forming operation; a bell crank lever positioned to engage and eject the formed work; and a pawl coupled with said rack and in escaping relation with the bell crank when the rack is moving in a functioning direction and having operating engagement with said lever when the rack is moving in its non-operating stroke.

5. A forming machine including two anvils 105 each having an arcuate work engaging surface; two work engaging members each anvil having a work engaging member individual thereto and coaxial therewith; and means for effecting relative rotation of each anvil and the work engaging member individual thereto, in the forming operation, and oppositely to the direction of the relative rotation of the other anvil and work engaging member related thereto.

6. A forming machine including two anvils 110 each having an arcuate work engaging surface; two work engaging members each anvil having a work engaging member individual thereto and coaxial therewith; two gears, each anvil and the cooperating work engaging member having a gear individual thereto, which is connected with one of these elements to turn it with respect to the other; two operating reciprocating racks, each of the aforesaid gears having such a rack individual thereto and in mesh therewith; and means for reciprocating said racks in opposite directions.

7. A forming machine including two an-

vils each having an arcuate work engaging surface; two work engaging members each anvil having a work engaging member individual thereto and coaxial therewith; two gears, each anvil and the cooperating work engaging member having a gear individual thereto, which is connected with one of these elements to turn it with respect to the other; two operating reciprocating racks each of the aforesaid gears having such a rack individual thereto and in mesh therewith; gearing in mesh with both of said racks and effecting reciprocation thereof in opposite directions; and a reciprocable rack in mesh with said 15 gearing.

8. A forming machine including two anvils each having an arcuate work engaging surface; two work engaging members, each anvil having a work engaging member individual thereto and coaxial therewith; two gears, each anvil and the cooperating work engaging member having a gear individual thereto, which is connected with one of these elements to turn it with respect to the other; two operating reciprocating racks each of the aforesaid gears having such a rack individual thereto and in mesh therewith; gearing in mesh with both of said racks and effecting reciprocation thereof in opposite directions; 30 a rack in mesh with said gearing; and tripping mechanism in actuating relation with the latter rack.

9. The structure of claim 7 wherein the gearing is inclusive of two gears of different diameters, one in mesh with one of the racks operated by the gearing, and the other in mesh with the other rack operated by the gearing, the work engaging surface of the anvil that is associated with the rack that is operated by 40 the gear of smaller diameter being of shorter radius than the work engaging surface of the other anvil.

10. The structure of claim 8 wherein the gearing is inclusive of two gears of different diameters, one in mesh with one of the racks operated by the gearing, and the other in mesh with the other rack operated by the gearing, the work engaging surface of the anvil that is associated with the rack that is operated by 50 the gear of smaller diameter being of shorter radius than the work engaging surface of the other anvil.

In testimony whereof, I hereunto subscribe my name.
